LIFE SAVING AND RESCUE REEL

George E. Beiderwell, Box 359, Paducah, Ky. 42001

Filed Apr. 6, 1967, Ser. No. 6,558

Term of patent 14 years

(Cl. D41—1)

FIG. 1

FIG. 2

FIG. 4

FIG. 3

FIG. 1 is a perspective view of a life saving and rescue reel;

FIG. 2 is a top view showing the winding knob in a forward position and the line, snap-hook and carrying cord omitted for ease of illustration;

FIG. 3 is an elevational view of the side opposite that in FIG. 1, portions being broken away for ease of illustration; and

FIG. 4 is a rear view thereof.

I claim:

The ornamental design for a life saving and rescue reel, as shown and described.
